UNITED STATES PATENT OFFICE.

HOVCEP SARAFIAN, OF TITUSVILLE, PENNSYLVANIA.

DESIGN FOR ORIENTAL CARPET.

SPECIFICATION forming part of Design No. 32,866, dated June 19, 1900.

Application filed April 20, 1900. Serial No. 13,667. Term of patent 7 years.

To all whom it may concern:

Be it known that I, HOVCEP SARAFIAN, a citizen of the United States, and a resident of Titusville, in the county of Crawford and State of Pennsylvania, have invented and produced a new and original Design for an Oriental Carpet, of which the following is a full, clear, and exact description.

Reference is to be had to the accompanying drawings forming a part of this specification, in which the figure is a face view of an oriental carpet, showing my design.

The design in its entirety consists of a band appearing composed of adjacent parallel rows of stitches A, somewhat spaced and terminating alternately on opposite sides of the band in short rows of close stitches B, alternating with a contrasting background C.

The leading feature of the design consists of the band-like figure having short rows of 20 stitches appearing alternately at the sides of the band.

Having thus fully described my invention, I claim as new and desire to secure by Letters Patent—

25 The design for a carpet, as herein shown and described.

In testimony whereof I have signed my name to this specification in the presence of two subscribing witnesses.

HOVCEP SARAFIAN.
